United States Patent Office.

JOSEPH R. BAILEY, OF WOONSOCKET, RHODE ISLAND, ASSIGNOR TO HIMSELF AND SELDEN A. BAILEY, OF SAME PLACE.

Letters Patent No. 98,837, dated January 18, 1870.

IMPROVED TOOL-HOLDER.

The Schedule referred to in these Letters Patent and making part of the same.

To all whom it may concern:

Be it known that I, JOSEPH R. BAILEY, of Woonsocket, in the county of Providence, and in the State of Rhode Island, have invented a new and useful Improved Tool-Holder; and I do hereby declare that the following is a full, clear, and exact description thereof, reference being had to the annexed drawings, making part of this specification, in which—

Figure 1 is an elevation, and

Figure 2, a transverse section.

Corresponding letters refer to corresponding parts in both figures.

The nature of my invention consists in providing a cheap and effective device for confining tools used in turning or planing metals.

To enable those skilled in the art to make and use my invention, I will proceed to describe its construction and operation.

In the drawings—

A represents a bar of iron, in the upper edge of which a dovetailed groove is formed, extending from one end to the other. The groove may be a little slanting, as shown in fig. 2, and its base bevelled, to

conform it to the form of the tool which is to be slid into it.

B represents another bar of iron, similar to A. This bar B has a groove formed in its under edge, tapering from bottom to top, as shown in fig. 2, and also somewhat slanting.

C represents the tool, which is slid into the groove in the bar A, after which the bar B is placed over its projecting part. The whole is then placed in the tool-post, and the set-screw therein screwed down upon the bar B sufficiently tight to hold the two parts of the holder, as well as the tool itself, firmly in position.

What I claim as new, and desire to secure by Letters Patent, is—

The tool-holder A B, constructed substantially as shown and described.

The above specification signed by me, this   day of   , 18

JOSEPH R. BAILEY.
